UNITED STATES PATENT OFFICE.

HERMAN ABRAMS, OF PHILADELPHIA, PENNSYLVANIA, ASSIGNOR TO CRESCENT
BRASS MFG. CO., OF READING, PENNSYLVANIA, A CORPORATION OF PENNSYLVANIA.

DESIGN FOR A PLATE FOR LIGHTING FIXTURES.

Application filed January 8, 1926. Serial No. 16,003. Term of patent 7 years.

To all whom it may concern:

Be it known that I, HERMAN ABRAMS, a citizen of the United States, residing at Philadelphia, in the county of Philadelphia and State of Pennsylvania, have invented a new, original, and ornamental Design for a Plate for Lighting Fixtures, of which the following is a specification, reference being had to the accompanying drawing, forming part thereof.

Fig. 1 is a side elevation showing my new design.

Fig. 2 is a fragmentary portion of a bottom view showing a portion of the center, one complete arm, part of a second arm, and a section of the outer ring, in full lines with ornamentation complete, it being understood that such ornamentation is repeated throughout the entire periphery and on the radial arms and the center.

I claim,

The ornamental design for a plate for lighting fixtures, as shown.

HERMAN ABRAMS.
